APPARATUS FOR COATING AND WRAPPING PIPE

William Davis Moore, Birmingham, Ala., assignor to American Cast Iron Pipe Company, Birmingham, Ala., a corporation of Georgia

Application October 25, 1939, Serial No. 301,267

8 Claims. (Cl. 25—38)

This invention relates to apparatus for coating and wrapping pipe, and among other objects aims to provide an improved machine for coating and wrapping metal pipe with a layer of cementitious material on the outside thereof, whereby external corrosion of the pipe is reduced or prevented. Of the common forms of underground corrosion attacking pipe lines, one of the more troublesome is the galvanic type of corrosion such as that caused by oxygen concentration cells in which a current is induced between well aerated and poorly aerated sections of the pipe wall. The outer layer of cementitious material applied by the apparatus of the invention will practically prevent this type of corrosion. Chemical corrosion of the pipe wall by strongly acid or so-called "alkali" soils is also largely nullified by the protective coating. Where the pipe line is subjected to the action of stray current electrolysis the protective layer reduces the intensity of the attack by preventing localization of this type of action.

It is well known that cast iron pipe, under ordinary conditions, will last for over 100 years. Under certain unusual conditions, any metallic structure, even cast iron pipe, will fail because of electro-chemical action. To meet such unusual conditions it is highly advantageous to provide metallic pipe with a protective outer layer of material which is relatively inert chemically and which will prevent or reduce the attack due to any electrical or chemical action known to occur in the soil. According to the present invention, apparatus is provided which is advantageously used at the pipe factory for coating pipe with a layer of reinforced cement mortar of substantial thickness, thus protecting the outer surface of the pipe against corrosion.

The present application is a companion to an application filed by me on the same day, Ser. No. 301,268 describing and claiming the preferred process, while the product thereof is claimed in my pending application, Serial No. 402,527, a division of application Serial No. 301,268.

In the accompanying drawings forming a part of this specification—

Fig. 1 is a side elevation of the preferred apparatus, showing a pipe in position for coating and wrapping;

Fig. 2 is a top plan view;

Fig. 3 is an end elevation;

Fig. 4 is a horizontal section on line 4—4 of Fig. 1; and,

Fig. 5 is a sectional elevation of a slightly modified form of hopper which may be used with the apparatus fully shown in other figures.

Referring particularly to the drawings, pipe length 11 is supported to rotate on its axis by any desirable means, for example the means

shown in the drawings, said means comprising a pair of plugs 12 and 13 adapted to fit respectively into the bell and spigot ends of the pipe, each plug being shown as having set screws 14 engaging the inside of the pipe with their outer ends. The plugs 12 and 13 have integral shaft extensions 12a and 13a and shaft extension 13a may simply rest in a bearing or journal 15, supported by a stand 16. The shaft extension 12a is joined by a shaft coupling 17 with a mechanical drive, here shown as comprising shaft 18, a large pulley 19 secured on shaft 18, a belt 20 driving the large pulley 19, a small pulley 21 driving the belt, shaft 22 on which pulley 21 is mounted, a speed reducer 23 driving shaft 22, and a variable speed electric motor 24 coupled to the speed reducer 23. By the described construction, the pipe 11 is rotated at any speed desired on its axis, and yet may be easily removed and replaced by another pipe length.

Arranged to travel longitudinally above the pipe 11 is a car 25 which comprises essentially a platform or truck, supported on four flanged wheels 26 which roll over a pair of rails 27 forming a track. The rails 27 are supported on a plurality of stands 28 and said rails are necessarily parallel to the longitudinal axis of the pipe so that the car moves parallel to said axis. It is within the scope of the invention to arrange the parts so that the car travels on either side of the pipe. Carried upon the car 25 is a bin or hopper 30 whose open top is adapted to receive cement mortar by gravity from a mixing machine or bin (not shown) which preferably is located above the car near one end of the machine. The lower or delivery end of the hopper is centered relative to the axis of the pipe, as best shown in Fig. 3, and the outlet of the hopper is preferably located not more than an inch or so above the top of the pipe, as shown.

In accordance with the invention, a strip of coarse-meshed, loosely woven, water-absorbing cotton cloth is spirally wrapped under tension about the pipe 11, initially on the outside of the cement layer 31 deposited upon the pipe from the hopper. The cotton strip is of such coarse mesh that some of the cement mortar will pass through the interstices of the meshes and thus will form a thin layer on the outside of the cotton wrapping, the result being that the cotton wrapping becomes imbedded in the cement mortar. The cotton wrapping used contains no oil or wax and thus is quite different from burlap which because of its oil or waxy content actually repels cement and thus cannot be integrally incorporated in the cementitious layer in accordance with the process. The preferred cotton wrapping readily absorbs the moisture of the cement mortar and its fibers take up part of the cement itself so that the fabric ultimately

becomes an integral part of the protective layer placed upon the pipe by the machine of the invention. Further advantage of such cotton wrapping is the fact that it will stretch when first absorbing moisture and will contract with the cement as the latter sets, dries and hardens, thus obviating separation of the wrapping from the cement. In the aforesaid companion application, the cotton fabric is disclosed more fully.

The machine of the invention provides means to lay the described cotton fabric spirally about the pipe as the cement mortar is deposited on the top of the pipe. The strip of fabric 32 is rolled on a spool 33 removably carried upon a pair of brackets 34 secured to the platform of car 25. Thus a new supply of wrapping may be added from time to time. The strip 32 passes from the spool 33 to a concave roller 35 which has a flange 35a on the lead end. The edge of this flange is adapted to roll on the pipe just in advance of the coating material as the latter is fed from the bin. Roller 35 is carried by a pivoted frame comprising a pair of parallel arms 36 having vertically adjustable pivotal connections 37 with two parallel, vertical hangers 38 secured to and depending from the car. Preferably the bin 30 is also supported upon the two arms 36 by pivotal connections 30a at its lower end (Fig. 3). Thus the flange 35a on roll 35 regulates the height of the discharge end of the bin above the top of the pipe; and if it is desired to vary the thickness of the cement layer, obviously a roll having a flange of a different height will replace the roll in use, or several sizes of flanges 35a may be attached at different times to the same roll.

To tension the textile strip properly, a coil spring 39 is provided bearing against a friction block 40 in turn frictionally retarding rotation of spool 33. Tension of spring 39 may be regulated if desired. This or an equivalent resistance is very important because otherwise the cement mortar would not be forced through the interstices of the loosely woven fabric strip nor would the fabric strip by its tension force the layer of the cement firmly against the outer surface of the pipe. The frictional means shown and described is, of course, merely illustrative and more or less diagrammatic and other fabric-tensioning means known in the textile arts may be employed.

To insure uniform and continuous travel of the car from one end of the pipe to the other, a power-driven, horizontal lead screw 41 extends the length of the machine and engages a nut 42 rigidly secured to the car. The lead screw is rotatably supported at its ends and at other points (not shown) if desired, and is driven as for example by gears 43 and 44 (Fig. 1), gear 44 being secured to shaft 18. Thus movement of the car synchronously with rotation of the pipe is effected. In lieu of this arrangement the car may be pushed by hand along the track or it may be pulled back and forth by a power-actuated cable or may be otherwise driven. Whether hand or machine operated, the movement of the car should be so governed that the cotton fabric is spirally wrapped with an overlap and this overlap may be approximately one inch for a medium size pipe. For a large pipe, employing wider textile strips, the overlap would be larger. Due to the angle of the axis of the roll 35 (which may be varied by means not shown), also because of the tension imposed upon the material and the rotation of the pipe, the

car may be moved along the track without any power except that received through the textile strip; and in such a case, an attendant may restrain or advance the car, by hand, as seems necessary, keeping a constant eye on the wrapping operation.

To smooth out the surface of the pipe coating, thus eliminating any ridges or other irregularities, a roller 45 is rotatably mounted on a frame 46 hinged as at 47 to car 25, and is adapted to bear on the top of the coated pipe. The axis of rotation of roller 45 preferably lies in the same vertical plane with the axis of the rotating pipe, and said roller may be heavy enough to exert a definite squeezing or ironing action. Obviously, roller 45 need not be attached to the car, but could be separately carried, as from a monorail, not shown.

When the machine is to wrap a pipe, one end of the fabric strip is tied adjacent one end, preferably the bell end, of the pipe. Then the machine is started, and the car runs until the fabric strip reaches the spigot end. The machine is stopped and the strip is then cut and wrapped by hand circularly around the spigot (leaving its extremity bare so that it may fit in a bell to make a tight joint) and is tied again. This may be done after removal of the pipe length from the machine. A poultice of cement mortar may be applied by hand to the outer surface of the wrapping if exposed at either end of the pipe. After the pipe is laid in the trench, any uncovered portions at the joints will be completely coated with cement, to insure complete protection of the entire outer surface of the pipe. The described machine is ready to wrap a new pipe length when the car is returned to its initial starting point, as by reversing motor 24.

If desired, a pneumatic vibrator (not shown) which vibrates the side of the hopper may be employed to prevent cement mortar from sticking to and setting upon the inside walls of the hopper. Preferably after the wrapping is completed, but before removal of the pipe length, a thin finishing coat of cement mortar is either plastered by hand or sprayed by a spray gun upon the outer surface of the revolving coated pipe.

Referring to Fig. 5, there is shown a modification of the hopper. Here the hopper 48 has a screw conveyor 49 at its lower end and extending through a hopper extension 50 to the discharge opening 51 which is directly above the top of the pipe (the same as in Fig. 3). The shaft of the screw conveyor is preferably driven by a variable speed motor and speed reducer (not shown) mounted on the car. This arrangement insures a more uniform feed of the cement mortar upon the pipe and is particularly desirable when using the same apparatus to coat different sizes of pipe, as a 12 inch pipe will take many times the amount of cement mortar that is required to coat a 6 inch pipe.

A particular feature of the invention is the provision of means for insuring the imbedding of the coarse meshed fabric in the body of the cement mortar, which is brought about by the tensioning and feeding means for the fabric. It will be clear from Fig. 3 that the fabric is pressed by the weight of roller 35, plus the weight of the hopper and its charge of cement mortar, into the surface of the cement mortar layer 31 on the pipe. The tension on the fabric causes it to become integrally incorporated in the cement mortar layer, and this incorporation is per-

fected by the ironing effect of roller 45. Thus the fabric may become so much a part of the cement layer that its strands may be practically indistinguishable from the cement, or may even be completely hidden by an outer thin skin or layer of cement, as more fully disclosed in the companion application.

Among the advantages of the apparatus are, its simplicity, its adjustability, inexpensiveness and economy of operation. It makes possible the production at the pipe factory of pipe which will prevent or reduce the corrosion due to any known soil and/or electrolytic conditions.

Obviously the present invention may be embodied in several forms neither described nor shown, and many changes in the described apparatus may be made in addition to those described herein.

Having described a preferred embodiment of the invention, what I claim as new and desire to secure by Letters Patent is:

1. A machine of the class described comprising, in combination, a pipe support for holding pipe against any movement except rotation; means to rotate the pipe about its longitudinal axis while on said support; a traveling hopper having an outlet adjacent the pipe, said hopper being adapted to receive a supply of cement mortar and to discharge the same upon the rotating pipe; means for holding a supply of fabric; tensioning means for the fabric; means to feed the tensioned fabric to the pipe adjacent the point at which the cement mortar is dumped; the means for holding the supply of fabric comprising a spool which travels with the hopper; said fabric being guided by a roller to the upper part of the pipe; said roller traveling with the spool and having a flange whose edge has rolling contact with the surface of the pipe; and means for mounting said roller so that it may rise and fall on the surface of the pipe.

2. A machine of the class described comprising, in combination, a pipe support for holding pipe against any movement except rotation; means to rotate the pipe about its longitudinal axis while on said support; a traveling hopper having an outlet adjacent the pipe, said hopper being adapted to receive a supply of cement mortar and to discharge the same upon the rotating pipe; means for holding a supply of fabric; tensioning means for the fabric; means to feed the tensioned fabric to the pipe adjacent the point at which the cement mortar is dumped; the hopper being supported on a vertically movable frame; the fabric-feeding means comprising a roller also mounted on the frame, said roller having a flange which rides directly on the pipe adjacent the hopper outlet; and means for adjusting the position of the frame relative to the pipe, said means also adjusting the position of the roller relative to the pipe.

3. A machine of the class described comprising, in combination, a pipe support for holding pipe against any movement except rotation; means to rotate the pipe about its longitudinal axis while on said support; a traveling hopper having an outlet adjacent the pipe, said hopper being adapted to receive a supply of cement mortar and to discharge the same upon the rotating pipe; means for holding a supply of fabric; tensioning means for the fabric; means to feed the tensioned fabric to the pipe adjacent the point at which the cement mortar is dumped; means being provided to support the hopper on the pipe with its outlet spaced from the top of

the pipe; and conveyor means positively to feed cement mortar from the outlet of the hopper.

4. A machine of the class described comprising, in combination, a pipe support for holding pipe against any movement except rotation; means to rotate the pipe about its longitudinal axis while on said support; a traveling hopper having an outlet adjacent the pipe, said hopper being adapted to receive a supply of cement mortar and to discharge the same upon the rotating pipe; means for holding a supply of fabric; tensioning means for the fabric; means to feed the tensioned fabric to the pipe adjacent the point at which the cement mortar is dumped; the fabric-tensioning means comprising a frictional resistance retarding rotation of a spool holding a supply of the fabric, and the fabric-feeding means comprising a roller which rides directly on the pipe adjacent the hopper outlet; means connecting the hopper with said roller so that the hopper rises and falls with said roller; said fabric being led from the spool downwardly and part way around said roller and into contact with the cement mortar immediately after it is spread on top of the pipe.

5. A machine of the class described comprising, in combination, a pipe support; means to rotate the pipe about its longitudinal axis while on the pipe support, said means preventing any movement of the pipe other than rotation; a hopper having an outlet, said hopper being adapted to hold a supply of cement mortar and to discharge the same through the outlet in a layer upon the outer surface of the pipe; means to support the hopper on the surface of the pipe, said hopper-supporting means gaging the thickness of the layer of cement mortar; means to move the hopper along the length of the pipe; means to hold a supply of coarse meshed, water-absorbent fabric; means to tension the fabric as it is fed to the pipe; and means to guide the fabric and assist in wrapping it around the pipe as the pipe is rotated, said fabric-guiding means bringing the fabric against and outside of the cement mortar adjacent the point where said mortar is discharged upon the pipe.

6. The invention according to claim 5 wherein the means to move the hopper comprises a car or carriage which travels in a path parallel to the longitudinal axis of the pipe; the hopper-supporting means being pivoted upon the car or carriage and having a pivotal connection with the hopper and adapted to be supported on the pipe, whereby the hopper may move freely up and down relative to the pipe and independently of the car.

7. The invention according to claim 5 wherein the means to move the hopper carries a frame one end of which is pivotally connected to the means to move the hopper; said pivotal connection being vertically adjustable thereby to vary the position of the frame relative to the pipe; and means pivotally connecting said frame intermediate its ends to the lower portion of the hopper; said last named means being adjustable transversely of the pipe to vary the position of the hopper laterally relative to the pipe.

8. The invention according to claim 5, wherein the hopper-supporting means comprises a roller together with means pivotally connecting the roller to the hopper, said roller having a radial flange whose peripheral edge rolls on the bare pipe in advance of the discharge of the cement mortar.
